US00D561724S

(12) **United States Design Patent** (10) **Patent No.:** **US D561,724 S**
(45) **Date of Patent:** **** Feb. 12, 2008**

(54) **PORTABLE PHONE**

(75) Inventors: **Young-Sae Kim**, Palo Alto, CA (US);
Chi-Young Ahn, Seoul (KR);
Young-Ju Yeo, Seoul (KR);
Chang-Hwan Hwang, Goyang-si (KR)

(73) Assignee: **Samsung Electronics Co., Ltd.**,
Suwon -si (KR)

(**) Term: **14 Years**

(21) Appl. No.: **29/272,472**

(22) Filed: **Feb. 9, 2007**

(30) **Foreign Application Priority Data**

Sep. 29, 2006 (KR) 30-2006-0040078

(51) **LOC (8) Cl.** **14-03**

(52) **U.S. Cl.** **D14/138**
